UNITED STATES PATENT OFFICE.

BERNHARDT E. HENRIKSEN, OF SAN FRANCISCO, CALIFORNIA.

PNEUMATIC SAFETY-CLUTCH.

SPECIFICATION forming part of Letters Patent No. 223,287, dated January 6, 1880.

Application filed November 21, 1879.

To all whom it may concern:

Be it known that I, BERNHARDT E. HENRIKSEN, of the city and county of San Francisco, and State of California, have invented a 5 Pneumatic Safety-Clutch; and I hereby declare the following to be a full, clear, and exact description thereof.

My invention relates to certain improvements in elevators and hoists of any description such as are employed to convey goods and passengers; and its object is to secure the cages or platforms of such elevators or hoists against sudden falls, which are usually caused by the breaking of the cable or hoisting machinery.

My invention consists in the employment of a pneumatic fan or plate in connection with the elevator platform or cage and suitable mechanical devices, whereby any unusual 20 speed of the descending cage or platform will cause these devices to be actuated by the resistance of the atmosphere, and thus check or stop the speed of the platform.

Referring to the accompanying drawings for 25 a more complete explanation of my invention, Figure 1 is a front elevation of an elevator-cage illustrating my invention. Fig. 2 is a side section of the same.

A B C constitute the usual frame-work of 30 an elevator-cage. D is a light substantial fan or parachute secured beneath the platform. It will be manifest that this fan may be formed to operate in various ways; but in the present case I have shown it as a flat fan mounted horizontally upon a shaft, E, with bearings 35 upon the frame A. This shaft passes across near one edge of the fan, and the other edge is left free to move up and down, being counterbalanced by weights O, as shown.

40 F F are trip-levers, made in the present case somewhat in form like a bell-crank lever, and secured to the frame A so as to act upon the lower ends of the upright rods G G, which extend up beside the side timbers B of the cage, 45 and are connected by links with the axes of the movable cog-wheels and safety-catches H H. These catches have their outer faces made eccentric or cam-shaped, and are provided with holding-teeth, so that when they

are turned outward by the action of the rods 50 G and the cog-wheels they will engage with the guide-timbers and stop the cage.

I I are stationary toothed sectors, secured to the cage-frame so that the teeth of the cog-wheels H will mesh with them, and when 55 forced upward by the action of the rods G they will be rotated upon the circumference of the sector and carried outward by the curve, at the same time turning the holding-teeth upon the cam-face, so that these teeth will be 60 forced against the guide-timbers and the cage locked and prevented from any further descent.

Arms J J are journaled upon the cross-bar C of the cage, and have the weights K fixed 65 to one end, while the opposite end is connected with the axis of the cog and safety-catch H. These weighted arms serve to keep the gears in contact with the sectors, and also to act as counter-balances to throw the safety-catches 70 outward as soon as they are released by the action of the fan.

The operation of my device is as follows: Whenever, by accident or otherwise, the cage becomes released, so as to fall rapidly, this 75 rapid motion produces a compression of the air beneath, which will act upon the fan or parachute and force it upward. As it rises it will strike the trip-levers F, and by its action upon them it will release the rods G. The weights 80 K will then act upon the pinions H (by means of the arms J) and cause them to rotate upon the toothed sections I, which carries them outward, and at the same time turns them so that the toothed eccentric or cam-shaped outer faces 85 will be thrown into contact with the guide-posts M, so as to engage with them and act as safety-catches, thus holding the cage and preventing it from falling farther. These eccentrics or cam-shaped surfaces form a powerful 90 wedge-brake, the power of which increases with the strain which is brought upon them, and will instantaneously arrest the fall of the cage. By raising the weights K the trip-levers are again set, being self-acting.

95 It will be manifest that various means for arranging the fan may be devised. It may be supported upon a central stem, which may

move in guides and act upon the trip-levers or equivalent devices for causing the safety-catches to be thrown out when necessary.

Having thus described my invention, what I claim as new, and desire to secure by Letters Patent, is—

1. The improvement in operating the safety-catches of elevators, consisting of the fan or parachute D, suspended beneath the platform so as to be actuated by the current of air caused by a rapid descent of the platform, and connected with the safety-catches so as to throw them out by such action, substantially as herein described.
- 15 2. The fan D, supported from the cage or platform A, so as to be moved by the pressure of air caused by a rapid descent of the cage, and connected with the catches H by the rods G and trip-levers F, so as to cause said catches to act, substantially as herein described.

3. The eccentric or cam-shaped catches H, having gear-teeth upon their inner faces, and the corresponding toothed sections I, secured to the beams C, with which they mesh, in combination with the weighted arms J, whereby 25 the catches are thrown outward when released and into contact with the guide-posts, substantially as herein described.

4. The fan D, hinged or otherwise movably connected with the cage or platform A, in combination with the trip-levers F, rods G, safety-catches H, and weighted levers J, substantially as and for the purpose herein described. 30

In witness whereof I have hereunto set my hand.

BERNHARDT E. HENRIKSEN.
